UNITED STATES PATENT OFFICE.

J. J. McCORMICK, OF BROOKLYN, E. D., NEW YORK.

IMPROVEMENT IN SKATES.

Specification forming part of Letters Patent No. 38,907, dated June 16, 1863.

To all whom it may concern:

Be it known that I, J. J. McCORMICK, of Brooklyn, in the county of Kings and State of New York, have invented a new and useful Improvement in Skates; and I do hereby declare that the following is a full, clear, and exact description of the same, reference being had to the accompanying drawings, forming part of this specification, in which—

Figure 1 represents a plan or top view of my invention. Fig. 2 is a sectional side elevation of the same.

Similar letters of reference in both views indicate corresponding parts.

This invention consists in a skate having the foot-stand with a socket for the heel struck up of one piece of metal, and provided with spring-clamps in front and with a set-screw behind, in such a manner that a firm, cheap, and durable support for the foot is provided, and that by drawing the spring-clamp over the edge of the sole of the boot or shoe to which the skate is to be secured and screwing up the set-screw against the heel the skate is firmly retained in place.

To enable others skilled in the art to make and use my invention, I will proceed to describe it.

A represents the foot-stand of my skate, and B the runner. The foot-stand is struck up of one piece of sheet metal, and it is provided with a socket, a, to receive the heel of the boot or shoe to which the skate is to be fastened. Said foot stand corresponds in size and shape exactly to the boot or shoe to which it is to be secured, and it is furnished with a set-screw, b, behind to bear against the rear end of the heel, and with two spring-clamps, c, in front to catch and retain the front part of the sole. These clamps must be adjusted exactly to the width of the sole to which they are to be fastened, and they may be made adjustable by means of screws working in slots, so that they can be readily set to fit to soles of different widths. The runner is secured to the foot-stand by means of screws or rivets,

and the whole skate is exceedingly light and graceful.

By having the foot-stand with the socket all out of one piece my skate is rendered superior in durability to skates of the ordinary construction, there being no part which can possibly work off; and, furthermore, the heel is firmly held in place, and the set-screw b is not liable to tear off the socket.

The foot-stand, being made to correspond exactly to the shape of the foot, supports the same throughout, and the operation of skating is rendered less tiresome with my skates than with skates of the ordinary construction.

My skates can be fastened on the feet in a few seconds simply by slipping the feet into the clamps and tightening the set-screw.

The clamps c may be made of sheet-steel or other suitable material, and they are secured to the front part of the foot-stand, so that they catch over the edge of the sole of the boot or shoe to which they are to be attached. They are made to conform exactly to the shape of the sole, and when once adjusted they are not disturbed.

If it should be desirable for a still more secure fastening of the skates, straps may be employed, which pass through loops b, secured to the foot-stand, as clearly shown in the drawings.

What I claim as new, and desire to secure by Letters Patent, is—

1. A foot-stand, A, for a skate, struck up with the socket a for the heel out of one piece of sheet metal, in the manner shown and described.

2. As a new article of manufacture, a skate having a foot-stand with socket for the heel struck up out of one piece of sheet metal, and provided with a set-screw, b, and spring-clamps c, as and for the purpose specified.

J. J. McCORMICK.
